CLAIM

I claim the ornamental design for a rotating, sliding activator spool for dual neck pedal steel guitars, as shown and described.

DESCRIPTION

FIG. 1 is a perspective view of a rotating, sliding activator spool showing my new design;

FIG. 2 is an enlarged left side view of FIG. 1;

FIG. 3 is a front view thereof, the rear view is a mirror image thereof;

FIG. 4 is a top view thereof;

FIG. 5 is a bottom view thereof;

FIG. 6 is a right side thereof;

FIG. 7 is an elevation view showing the mounting of rotating, sliding activator spool on a dual neck pedal steel guitar shown in dotted; and,

FIG. 8 is top view of dual neck pedal steel guitar shown in dotted with the rotating, sliding activator spool shown in the mounting thereof.
